UNITED STATES PATENT OFFICE.

HIRAM R. SIMPSON, OF SAN FRANCISCO, CALIFORNIA.

LOCK SEAL.

Application filed May 26, 1925. Serial No. 32,973.

This invention relates to the class of locks and latches, and particularly to seals therefor, and has for its primary object the provision of a seal which will positively prevent actuations of the bolt except by authorized persons, notwithstanding the fact that a duplicate or master key of the lock may be in the possession of someone else, who, without authority or proper privilege, might attempt to effect or force an unlawful entry to the container of which the lock is a part.

My invention is particularly designed for use in connection with the safe deposit boxes generally found in banks, storage houses, commercial institutions, depositories or the like for locks of the swinging or lever tumbler type employing a flat sheet metal key. In banks or similar institutions where safe deposit boxes are rented by the customers, the customer is supplied with a key which is adapted to function in connection with a set of swinging tumblers of a lock so as to operatively control same after the tumblers are first partly actuated by the action of a master key. My invention is directed to a seal which can be under the control of the customer so as to ordinarily close the lock barrel against entrance thereto of spurious keys or devices, and the said seal is so designed that it passes through the key slot of the barrel in a manner that will permit it to be successfully operated by a co-acting releasing instrument in the hands of an unauthorized person.

In these safe deposit boxes of banks or similar institutions, it is sometimes necessary that the box be sealed so that the lawful subscriber or customer cannot enter it. This occasion arises sometimes as a matter of law, where it is demanded that the box be sealed in a way that it cannot be opened by anyone, the officials of the bank being perhaps the custodians of the box in such event. In view thereof, it is a very important object of my invention to provide sealing means consisting of interchangeable devices, one of which may be substituted for the other so that at times the sealed box will be exclusively under the control of the officials of the bank or someone other than the subscriber or customer.

Another object of my invention is to provide an article of this character which will fit the slot of the barrel and engage with the tumbler or tumblers so as to prevent an ordinary

key from being successfully passed through said slot and engaged with the tumblers.

With the above and other objects in view which will appear as the nature of the invention is better understood, the same consists in the improved construction and novel arrangements of parts which will hereinafter be fully described and particularly pointed out in the claims.

In the accompanying drawings has been illustrated a single and preferred form of the invention, it being, however, understood that no limitations are necessarily made to the precise structural details therein exhibited, but that changes, alterations and modifications within the scope of the claims may be resorted to when desired.

Figure 1 is a front view of a lock showing my seal operatively engaged therewith;

Figure 2 is a similar view with the front plate of the lock removed;

Figure 3 is a section on line III—III of Figure 2;

Figure 4 is a view similar to Figure 3 showing the seal arresting and releasing means in place in the keyhole of the lock alongside the seal to release the tumbler mechanism from the seal and permit the latter to be withdrawn preparatory to the operation of inserting the regular key in the barrel;

Figure 5 is a view in side elevation of one of the arresting and seal removing elements;

Figure 6 is a view in side elevation of the form of seal used in conjunction with the arresting element shown in Figure 5;

Figure 7 is a view of another form of interchangeable seal arresting and extracting element;

Figure 8 is a view similar to Figure 6 of a form of seal with which the element in Figure 7 is adapted to coact; and

Figure 9 is a top edge view of either one of the seals shown herein.

While I have described the use of my invention in connection with the safe deposit boxes of banks or similar commercial institutions, this shall not be considered a limitation.

The lock shown herein is of any suitable well known construction consisting of a set of swinging type of tumblers 10, two revolvable key barrels of which 11 is the one

under the control of the so-called master key, and 12 is the one under the control of the customer.

Both of these barrels are arranged to extend transversely under the tumblers, and the one indicated at 11 coacts with a key whose wards are adapted to permit of actuation of certain of the tumblers and which key is called the master key, which in the case of safe deposit box locks is held by the bank. The other barrel 12 is adapted to function with the customer's key, whose wards are designed to function with respect to the other of the tumblers so that all of the tumblers may be ultimately moved with respect to the bolt.

The bolt 14 is also of the customary type adapted to be respectively locked and released by all of the tumblers. As the elements of the lock are of the usual well known construction, it is believed that the description recited in the foregoing will be sufficient for every purpose of demonstrating its operativeness in conjunction therewith of my invention.

In Figure 5 is shown in detail what I describe as a seal arresting and extracting element 15, the same being struck from a single piece of flat sheet material, preferably metal, so as to provide at its front end a rounded nose 16 whose upper surface merges into a cam face 17, which latter leads on to a tumbler sustaining surface or shoulder 18 on the upper edge of the forward portion of the blank. This shoulder or sustaining surface is proportioned so as to accommodate a single tumbler, preferably the front one of the group employed in the present lock.

On the under side, at a point midway between the ends of the blank, is formed an extracting lug 19 whose vertical shoulder 20 merges onto an undercut or cam surface 21 on the bottom edge of the blank. The outer end of the blank is formed with a perforation 22 whereby it may be carried on a pocket chain, key ring, or other loss preventing device capable of being worn on the person of the user.

In Figure 6 I show in detail the form of barrel seal and tumbler locking mechanism used in conjunction with the seal extracting element 15. This seal is struck preferably from a single piece of metal or material of a color corresponding with that of the element 15. The seal is substantially flat and is formed with a nose 23 which merges into an inclined cam face 24 extending in the direction of a tumbler receiving recess 25. At the lower outer corner of the blank, same is curved outward at 26, upward at 27, and laterally at 28 forming an arm, on which latter portion is formed a finger 29.

In Figure 7, a tumbler elevating and seal extracting element 30 is shown. This is struck also from a sheet of flat material, and

very closely resembles the form in Figure 5. It is, however, of a different color or suitably formed so as to be distinguished therefrom. The forward end of this blank has a nose 31, a tumbler receiving cam surface 32 and a tumbler sustaining surface or shoulder 33, in this instance the shoulder being proportioned to accommodate the first two tumblers of the group. Under the blank between the ends thereof is an extracting lug 34 arranged in front of a guiding or cam surface 35 on the lower edge of the blank.

The seal arresting and tumbler elevating element 30 shown in Figure 7 coacts with a seal of corresponding color, the same shown in Figure 8. For practically all intents and purposes, this seal is in substantial agreement with the one shown in Figure 6, except that the tumbler recess 36 is formed nearer the front end or nose 37 than is the case with the form shown in Figure 6 so that it will engage beneath and finally receive the lower front edges of the two front tumblers of the group.

Assuming that the bolt of the lock has been projected to secure the door of the safe deposit box in a closed or locked condition, the seal shown in Figure 6 is inserted nose end 23 into the slot of the barrel 12, sufficient pressure being exerted thereagainst so as to force it far enough into the barrel to cause its finger 29 to engage with the front face of the escutcheon, the latter acting as a stop. The seal is now accurately positioned with respect to the tumblers, and the first tumbler of the group has fallen into the recess 25. The seal now acts more or less as a slug, as it almost closes the key slot of the barrel being in fact half the thickness of the regular flat key. In view thereof, it is impossible for one other than the authorized party to insert a key in the slot of the barrel unless this slug or seal is removed. When the seal is in its tumbler engaging or active position, the said finger 29 passes into the key guiding slot 38 of the escutcheon or rather the extension of the key slot formed in the fixed rim around the revolvable key barrel in this type of lock, thus preventing rotation of the barrel and seal.

Now, it shall be assumed that the authorized owner wishes to release the lock through actuations of his key, followed by actuations of the tumbler through a previous operation of the master key. The owner of course has in his possession the seal releasing device 15 and the nose end 16 of the element is now guided into the key slot of the barrel 12 alongside of and so as to come directly at one side of the seal or plug flatwise in the narrow width of the keyway. As it is advanced into the slot, the first tumbler of the group engages with the face 17 until it gradually rides on to the sustaining surface.

or shoulder 18. This elevates the tumbler out of the recess 25 of the seal device, and the recess is then closed or spanned by the adjacent end of the element 15.

5 It will be observed that the upper edge of the element 15 is cut away at 39 to provide a clearance so that the element 15 will compensate itself to the seal or lift slightly at its outer end and permit the lug 19 of the element to ride over and engage directly behind the shoulder 40 of the seal as shown in Fig. 4. The tumbler is now clear from the seal, and by drawing in an outward direction upon the element 15, it, together with the 10 seal, is extracted. When this is done, the lawful custodian of the box can insert the customary key into the barrel 12 in order that the bolt of the lock can be released from its keeper.

20 As previously stated, it is sometimes necessary to even prevent the lawful custodian of the key to the box from gaining access thereto. Sometimes this is required as an act of law, where the safety deposit box is 25 sealed by orders of the court so that the lawful custodian of the key, or subscriber to the box cannot at this time gain access thereto by means of his key. The seal used in conjunction with the element 15 is removed 30 by the proper authorities, and the one shown in Figure 8 substituted therefor, or applied to a customer's box which had no private seal in place. The only difference between the seal shown in Figure 8 and the one shown in Figure 6 is that the former accommodates two tumblers of the locking mechanism. This also applies to difference in construction of the element 30, Figure 7, over the form and construction of the element 15, 35 Figure 5.

I prefer that the seal shown in Figure 8 and the extracting element therefor shown in Figure 7 be of distinguishing colors from the color of the seal of Figure 6 and its extracting element, Figure 5, so as to make it indicative of the fact that this particular safe deposit box has been sealed by the authorities under special orders. This may be for legal purposes in the transaction of matters before a court, or it may be for delinquencies of the subscriber in paying dues or rentals for the box, or like causes.

50 A particular point to be noted is the fact that while the releasing and extracting device 15 will only release the seal or plug shown in Fig. 6, the device shown in Fig. 7 (normally in custody of the authorities) will release either of the seals shown in Figs. 6 and 8, and therefore the bank under proper

authorization can remove a customer's private seal and substitute one as per Fig. 8 which he cannot remove and consequently his box is locked against him, until aided by proper authorities to open it.

60 Also another point is, that the authorities' seal being of a distinctive color is instant notice to the attendant with the master key that the box is locked by authority.

65 The combined thickness of the extracting element and the seal which coacts therewith is about equal to the thickness of the key which would engage the slot of the barrel in which these elements fit.

I claim:

1. In a tumbler lock provided with a revolvable key barrel having a key slot and a notched fixed rim, a plug device adapted for insertion in the key slot and formed for engagement with a tumbler against withdrawal, said device formed with a finger 75 engaging the notch when the device is in position.

2. In a structure as specified in claim 1 said finger being carried on an arm extending laterally from the outer end of the 80 device.

3. In a tumbler lock provided with a revolvable key barrel having a key slot and a notched fixed rim, a plug device adapted for insertion in the key slot and formed 90 for engagement with a tumbler against withdrawal, said device formed with a finger engaging the notch when the device is in position, said finger carried on an arm extending laterally from the outer end of the 95 device, and a plug extracting element slideable alongside of said plug into the slot adapted to release said tumbler and provided with a lug engaging said arm for withdrawal of the plug.

4. In a structure as specified in claim 3 100 said plug extracting element formed and adapted for bodily tipping at its outer end for engagement of said lug and arm.

5. In a tumbler lock of the safe deposit 105 box type provided with a revolvable key barrel having a flat key slot extending transversely past the tumblers, means substantially one-half the thickness of said key slot adapted for insertion therein and engageable with one of said tumblers against withdrawal, and means substantially one-half the thickness of said slot adapted for insertion therein alongside of said first mentioned means formed and adapted to release said 110 tumbler.

115 HIRAM R. SIMPSON.
